UNITED STATES PATENT OFFICE.

WILLIAM CULLEN MORRIS, OF NEW YORK, N. Y., ASSIGNOR TO THOMAS J. HAYWARD,
TRADING AS BARTLETT, HAYWARD & CO., OF BALTIMORE, MARYLAND.

LIQUID-SURFACE DRAIN FOR GAS-HOLDERS.

No. 914,293.

Specification of Letters Patent. Patented March 2, 1906.

Application filed February 5, 1906. Serial No. 414,307.

To all whom it may concern:

Be it known that I, WILLIAM CULLEN MORRIS, a citizen of the United States, residing at New York city, in the county of New York and State of New York, have invented certain new and useful Improvements in Liquid-Surface Drains for Gas-Holders, of which the following is a specification.

This invention relates to a liquid-seal surface-drain for gas holders and has for its object to provide a drain for receiving and carrying off the scum that collects on the surface of the water which forms the liquid seal between the several sections of the gas holder.

During the use of gas holders the surface of the water employed to effect a liquid seal between the gas-holder sections becomes fouled by the collection of oil and other substances, and the result is that as the inner shell or dome of the holder rises, because of the inlet of gas beneath it, the fouled substances on the surface of the water contact with the walls of the several sections and adhere thereto and cause damage to the walls as well as produce an unsightly appearance on the exterior. This objectionable feature necessitates a frequent painting of the gas-holder sections, which is an expensive operation and one object therefore of this invention is to provide a surface drain that will collect and carry off the scum and impurities from the surface of the water and thereby obviate the objectionable features heretofore referred to.

Another object of the invention is to provide for the removal of the surface scum from that portion of the gas holder where it contacts with the walls of the holder and to temporarily store the matter thus removed in a portion of the holder where it cannot produce the objectionable results referred to.

Another object of the invention is to provide suitable means on the interior of the holder for separating one portion of the liquid sealing surface from that portion which lies adjacent the walls of the holder so that the scum removed from that portion of the surface adjacent the walls may be temporarily stored in the removed portion.

Another object of the invention is to provide surface-drains that will extend around the holder adjacent to but spaced from the walls thereof, for collecting and drawing off the scum from the surface of the liquid-sealing medium, and to also provide a receiving

space within the area bounded by the drains for receiving the scum collected by the drains.

With these and other objects in view, the invention is illustrated in the accompanying drawings, in which,—

Figure 1, illustrates a plan view of the several sections of a gas holder,—the crown or dome of the holder being removed to illustrate the structural frame work employed to sustain the crown and also illustrates the collector trough or drain sustained by the framework. Fig. 2, shows a sectional elevation of the same. Fig. 3, illustrates an enlarged detail plan view of the collector; the post for sustaining the same; the vertical wall of the inner section and the drain pipes. Fig. 4, shows a vertical sectional detail through the collector trough,—the section being taken on the line 4—4 of Fig. 3. Fig. 5 illustrates an enlarged detail or side elevation of a portion of the trough. Fig. 6, shows a vertical sectional view through the trough and a side elevation of the discharge pipe,—the section being taken on the line 6—6 of Fig. 3, and Fig. 7, illustrates a front elevation of the trough and discharge pipe.

Referring to the drawings by numerals, 1, designates the supporting framework which may be constructed in any well-known or preferred manner. In the present instance this framework is provided with a plurality of vertical or upright posts, 2, which I propose in the present instance to utilize for sustaining the surface drain.

The innermost section or gas-holder proper comprises the cylindrical vertical wall, 3, and an arched dome or crown, 4, which may normally be sustained by the structural framework during the absence of gas. The several cylindric sections, 5, surround the inner section so as to operate in the usual manner.

The particular construction of the holder is immaterial and the same may be varied widely from that shown as the present invention does not reside therein.

While in the present instance a water supply pipe, 6, is provided for the purpose of supplying water to effect a liquid seal between the gas-holder sections, it is to be understood that any suitable form of water supply may be employed for this purpose and it should also be understood that rain water will also serve to provide a seal between the several sections.

By reference to Figs. 3, 4 and 5 it will be seen that the upright posts, 2, of the framework carry metal bracket arms, 7, the outer projecting ends, 8, of which incline downwardly and are curled over to form a hook, 9.

The trough into which the scum is to be drained has an outer circumferential wall, 10; an inner circumferential wall, 11, which is higher than the outer wall, and a flange, 12, which depends from and projects below the bottom.

The bracket arms which sustain the trough from the framework may be secured to the trough in any preferred manner but in the present instance the end, 8, of the arm, 7, extends over the lower outer wall and has its hook, 9, curled under the rolled or wired upper edge of said outer trough wall. An arm, 13, is bolted to the under side of the bracket, 7, and said arm extends downwardly and beneath the trough to form a bottom support therefor, as clearly shown in Fig. 4.

The position of the trough with respect to the vertical wall, 3, of the inner holder section is such as to leave a space, 14, between said trough and the vertical walls of the surrounding holder sections.

In the present instance the trough extends continuously around the framework and in substantially the same horizontal plane as the surface or level of the liquid sealing medium while the depending flange, 12, on the trough extends vertically below and is submerged in said liquid. This construction and arrangement of the trough and its pendent flange serves to separate the surface scum on the liquid in the space, 14, from the surface of the liquid in the space, 15, the liquid overflowing the lower outer wall, 10, into the trough.

The trough is provided with one or more outlets through which the substances flowing into it may be conveyed off. This outlet is best illustrated in Figs. 3, 6 and 7 and consists of a depending tubular pocket, 16, to the lower end of which is connected a vertical pipe, 17. This pipe, 17, extends downwardly in the inner shell, then turns laterally in a horizontal direction, at 18, at the bottom of said shell and extends beneath the telescoping surrounding sections, 5, then again extends vertically at, 19, between the outermost and the next adjacent sections, as shown in Fig. 2. At the upper end the vertical portion, 19, of this outlet pipe is connected with a pipe, 20, which has position in a horizontal plane below the trough and said pipe, 20, may lead to any suitable point of discharge but preferably leads to a pump indicated by the numeral, 21, in the drawings 60 which pump is located at any convenient point with respect to the gas holder.

By reference to Figs. 2 and 6 it will be seen that the overflow pipes, 17, 18, and, 19, together form a trap so the gas in the holder 35 cannot escape through said overflow.

The nature of the product that is drawn off from the surface of the sealing liquid in the space, 14, is such that it should not be emptied into streams or sewers, and it is desirable that it be disposed of in some other way. As this objectionable matter does not ordinarily accumulate fast enough to provide for its continuous disposal, it is preferable to allow the same to accumulate and be stored until a sufficient quantity has been stored to justify its removal economically.

In order to provide for the temporary storage of this drawn-off substance from the space, 14, I preferably run the pipe, 20, to the pump, 21, and to the latter I connect a pipe, 22, which returns to the gas-holder sections, as shown in Fig. 2. This latter pipe then extends downwardly between said sections and has a horizontal stretch, 23, at the bottom of the holder which enters into the inner shell where it turns upwardly at, 24, in the space inclosed by the trough, and the upper end, 25, of said pipe is curved over and downwardly so that the scum drawn off the sealing medium in the space, 14, is conveyed through pipe, 20, to the pump and from the latter through pipe, 22, back into the inner shell and deposited in the space, 15, which is inclosed by the trough and pendent flange, 12, thereon. By this means the central space, 15, in the inner shell may be utilized as a storage for the drawn-off scum until such time as it is desired to dispose of it, at which time the pump may be operated to draw the scum back through the curved end, 25, of the pipes, 24, 23, and, 22, then through pipe, 26, the valve, 27, being closed, and finally discharge it through pipe, 28. During this operation the valve 29, between pipes, 22, and, 28, will also be closed.

There may be times, for example, during rain storms when it is desirable to convey the overflow from the holder off to a point without having it pass into the central space, 15, of the holder and to do this I provide a valve, 30, between pipe, 26, and the pump, 21, which I may close so as to shut the overflow from the pump and allow it to pass through pipe, 26, directly into pipe, 28, in which event the valve, 29, will also be closed. A valve, 31, in the pipe, 26, when closed prevents the scum from passing direct to pipe, 28, when it is desired to pump it into the holder.

Having thus described my invention what I claim and desire to secure by Letters Patent is,—

1. The combination with a gas-holder comprising a stationary shell section and a movable shell-section having a liquid seal between them, of means within the movable shell-section and adjacent but independent of the walls thereof for receiving the substances from the surface of the sealing medium, and drain connections communicating

with said means for conveying said substances from the latter.

2. The combination with a gas-holder comprising stationary and movable shell-sections with a liquid seal between them, of means within the movable shell but independent of the wall thereof and extending around the latter for receiving the overflow from the surface of the sealing medium between the sections, and a drain leading from said receiving means and extending to the outside of the holder for conveying off the matter collected in the receiving means.

3. The combination with a gas-holder comprising a plurality of shell-sections, of means in the inner shell for dividing the space therein adjacent the liquid-sealing surface into a plurality of spaces, and means for conveying the substances from the surface in one space and depositing it in another space in the holder.

4. The combination with a gas-holder comprising a plurality of shell-sections containing a liquid sealing medium, of a drain extending around on the interior of the inner shell and adjacent the surface of the sealing medium,—said drain serving to receive the overflow from said surface of the liquid at one side of it, and means for conveying said overflow to the opposite side of the drain.

5. The combination with a plurality of telescoping gas-holder sections containing a liquid-sealing medium, of a receptacle within the said telescoping sections and spaced from and independent of the walls thereof,—said receptacle having position in a plane adjacent the surface of the liquid seal to receive the overflow therefrom, and means for conveying the overflow from said receptacle.

6. The combination with a plurality of telescoping gas-holder sections containing a liquid sealing medium, of a stationary receptacle within the holder and independent of the walls of the latter to receive the overflow from the surface of the liquid seal; a pipe for

conveying the overflow from said receptacle and a trap in said pipe.

7. The combination with a plurality of telescoping gas-holder sections containing a liquid sealing medium, of a trough in the inner section of said holder and having position adjacent to but spaced from and independent of the wall thereof,—said trough to receive the overflow from the surface of the liquid seal, and a pipe for conveying the overflow from the trough.

8. The combination with a plurality of telescoping gas-holder sections containing a liquid sealing medium, of a trough extending around the interior of the holder adjacent the surface of the liquid seal and spaced from and independent of the wall of the holder, a flange depending from said trough and a pipe for conveying the overflow from the trough.

9. The combination with a plurality of telescoping gas-holder sections containing a liquid sealing medium, of a trough extending around the inner section of the holder adjacent the surface of the liquid seal and spaced from and independent of the wall of the holder,—said trough having an inner wall that is higher than the outer wall thereof, and a pipe for conveying the overflow from the trough.

10. The combination with a gas holder comprising a plurality of shell-sections, of means in the inner shell for dividing the space therein adjacent the liquid-sealing surface into a plurality of spaces; a pump; a pipe for conveying the overflow from the liquid seal surface in one space in the inner shell to the pump, and a pipe for conveying the overflow from the pump and depositing it in the other space in the inner shell.

In testimony whereof I affix my signature in presence of two witnesses.

WILLIAM CULLEN MORRIS.
